COMBINED RECORD PLAYER AND RADIO

Youta Takashima, Naoko Hayashi, and Katuhiko Oikawa,
Moriguchi, Osaka, Japan, assignors to Sanyo Electric
Co., Ltd., Moriguchi, Osaka, Japan

Filed Apr. 17, 1973, Ser. No. 351,902

Claims priority, application Japan Nov. 29, 1972

Term of patent 3½ years

Int. Cl. D14—01, 03

U.S. Cl. D56—4 R

FIG. 1

FIG. 2

FIG. 3

FIG. 4

FIG. 5

FIG. 1 is a perspective view of part of the front, top and right side of a combined record player and radio showing our new design with the cover in closed position;

FIG. 2 is a view similar to FIG. 1 with the cover in open position;

FIG. 3 is a rear elevational view with the cover in closed position;

FIG. 4 is a left side elevational view thereof; and

FIG. 5 is a right side elevational view thereof.

We claim:

The ornamental design for a combined record player and radio, as shown and described.
